UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

BRAKING DEVICE.

Application filed January 10, 1921. Serial No. 436,242.

My invention relates to braking devices and more particularly to braking devices for controlling the feed of rock drilling mechanisms.

- 5 An object of my invention is to provide an improved braking device. A further object of my invention is to provide a simple and improved mechanism for controlling the strength of feed of rock drilling devices. 10 Other objects of my invention will appear in the course of the specification and the appended claims.

In the accompanying drawings I have shown for purposes of illustration one embodiment which my invention may assume in practice.

In these drawings,—

Fig. 1 is a central longitudinal section through the feed cylinder of a fluid pressure feeding device for rock drills, parts being broken away to show internal construction.

Fig. 2 is a transverse section on the line 2—2 of Fig. 1.

25 Figs. 3, 4, and 5 are fragmentary views through the control mechanism on the same section as that of Fig. 1 and showing the control valve in different positions.

In the illustrative embodiment of my invention, I have disclosed it used in connection with a feeding mechanism 1 of a rock drilling motor 2, the feeding mechanism comprising a cylinder 3, having a bore 4 in which a piston 5 is reciprocable in one direction under the action of fluid pressure and in the opposite direction due to gravity or force manually applied. The piston 5 is provided with a piston rod 6 connected to the rear head 7 of the rock drilling motor 2, and within the head 7 is arranged controlling mechanism generally designated 8 for controlling the operation of the feeding mechanism.

45 My improved braking mechanism consists essentially of a friction member 9 carried in a suitable elastic normally contracted carrier member 10 which is grooved as shown at 11 on its outer surface to receive the braking material. The carrier member 10 is carried in turn in an annular channel 12 formed in the periphery of the piston and of sufficient depth to permit the contracted carrier member 10 when not held out toward the walls of the cylinder to contract sufficiently to withdraw the friction material 9

from contact with the cylinder walls in such manner as to reduce, or entirely discontinue, its frictional effect on the cylinder bore.

To control the braking mechanism and likewise the feeding operation, I provide a control valve mechanism designated above as 8 and located on the base of the drilling motor consisting of a valve chamber 13 provided with a bushing 14 having a pair of ports 15 and 16 passing therethrough and carrying within the bushing a valve 17 adapted to receive pressure fluid in a central chamber 18 and to conduct it by way of ports 19, 20, and 21 in a manner hereinafter described.

The ports 19, 20, and 21 extend radially through the wall of the valve 17 and are arranged in a series in a single transverse zone about the periphery of the valve. Formed between the ports 19 and 20 is a groove 23 communicating with a suitable exhaust, not shown. A passage 22 extending longitudinally through the piston rod 6 serves to conduct the fluid admitted through the port 15 to the rear end of the feed cylinder 3 and causes forward feeding of the piston 5 and of the percussive tool as a whole. A passage 24 serves to conduct pressure fluid behind the friction member 9 and so to cause braking operation thereof. The valve 17 occupies four main positions in the control of the feeding mechanism, namely, those shown in Figs. 1, 3, 4, and 5.

In Fig. 1 the port 15 is shown in communication with the exhaust port 23 and accordingly there is no pressure tending to force the drill motor towards the work and also it will be noted that no pressure is being supplied to the passage 16 so that the device is not subjected to friction in its movements under manual control.

In Fig. 3, fluid is being supplied by way of port 20, passage 15 and passage 22 to the rear end of the feed cylinder and is causing forward feed of the drill motor.

In Fig. 4, fluid has been cut off from the passage 22 and fluid pressure is being supplied by way of passage 24 behind the friction member 9 and is retarding the feed.

In Fig. 5, pressure is being supplied through the port 21 in the valve, passage 15 and passage 22 to cause forward feeding of the drill motor, while the pressure behind the friction member 9 is being reduced by means of the fact that the exhaust port 23

is cracked while fluid is still supplied through port 19.

It will be obvious that by shifting the valve between positions 4 and 5, it will be possible to obtain a gradual feed under the control of the braking mechanism, the feed being retarded by placing the parts in position shown in Fig. 4 and accelerated in that shown in Fig. 5.

From the foregoing description and the several views of the drawing, it is believed that the operation of this device will be readily apparent without further detailed statement of its function.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:—

1. Drill feeding mechanism comprising a pair of telescopically related members having a range of relative movement greater than the length of the shorter one of said members and substantially equal to the difference in lengths of said members, means for effecting movement of one member relative to the other, means for causing variable friction between said members comprising an elastic annular brake carried by the moving one of said members and expandible by fluid pressure into engagement with the other, and unitary means operable at will to admit pressure fluid to said brake individually or to vent same.

2. Drill feeding mechanism comprising a pair of telescopically related members, means actuated by pressure fluid for moving one member on the other, means for causing variable braking action between said members comprising an elastic annular brake carried by one of said members and expandible by fluid pressure into engagement with the other, means for expanding said brake by admitting pressure fluid thereto independently of fluid supply to said telescopically related members, and a common control valve movable with said movable feeding member for both the feeding and braking means.

3. Drill feeding mechanism comprising a pair of telescopically related members, means actuated by pressure fluid for moving one member on the other, means for causing variable braking action between said members comprising an elastic annular brake carried by the inner one of said members and expandible by fluid pressure into engagement with the other, means for expanding said brake by admitting pressure fluid thereto individually, and common control

means for both the feeding and braking means comprising separate conduits in the inner member controlled by a single valve.

4. Drill feeding mechanism comprising a cylinder, a piston comprising a head and rod reciprocable in the cylinder, said head being reciprocable in said cylinder in a path of greater length than its own length and substantially equal to the difference between its length and the internal length of said cylinder, an annular brake band carried by said piston head in position to engage the cylinder wall and having a chamber provided behind it, and means individual thereto for admitting pressure fluid to said chamber at will, thereby expanding said band.

5. Drill feeding mechanism comprising a cylinder, a piston comprising a head and rod reciprocable in the cylinder, an annular brake band carried by said piston head in position to engage the cylinder wall and having a chamber provided behind it, and means individual thereto for admitting pressure fluid to said chamber at will comprising a conduit in said piston rod controlled by a hand operated valve.

6. Drill feeding mechanism comprising a cylinder, a piston comprising a head and rod reciprocable in the cylinder, means for admitting pressure fluid to said cylinder comprising a conduit in said piston, an annular brake band carried by said piston head in position to engage the cylinder wall and having a chamber provided behind it, means for admitting pressure fluid to said chamber comprising a second conduit in said piston, and a hand operated valve common to both said conduits.

7. Drill feeding mechanism comprising a cylinder, a piston comprising a head and rod reciprocable in the cylinder, means for admitting pressure fluid to said cylinder comprising a conduit in said rod, an annular brake band carried by said piston head in position to engage the cylinder wall and having a chamber provided behind it, means for admitting pressure fluid to said chamber comprising a second conduit in said rod, means for venting the brake and feed, and a hand operated valve having means for selectively supplying pressure fluid to either conduit alone or to both together and for venting the same.

8. Drill feeding mechanism comprising a cylinder, a piston movable therein by pressure fluid, a brake carried by said piston and movable radially thereof under the direct action of pressure fluid, control means comprising conduits formed in said piston and individual to said cylinder and brake respectively, and means for admitting pressure fluid thereto selectively.

9. Drill feeding mechanism comprising a cylinder, a piston movable therein by pressure fluid, a brake carried by said piston and

movable radially thereof under the direct action of pressure fluid, means comprising conduits formed in said piston and individual to said cylinder and brake respectively for admitting pressure fluid thereto, and a single valve provided with ports selectively movable into communication with either conduit alone or with both conduits at once.

10. Drill feeding mechanism comprising a cylinder, a piston movable therein by pressure fluid, a brake carried by said piston and movable radially thereof under the direct action of pressure fluid, means comprising conduits formed in said piston and individual to said cylinder and brake respectively for admitting pressure fluid thereto, a single valve provided with ports selectively movable into communication with either conduit alone or with both conduits at once, and means also controlled by said valve for venting the cylinder and brake.

11. Drill feeding mechanism comprising a cylinder, a piston movable therein by pressure fluid, a pressure fluid brake carried by the piston and engageable with the cylinder wall, and means including unitary valve mechanism operable at will to control the

flow of pressure fluid to the piston or brake individually.

12. Drill feeding mechanism comprising cylinder and piston elements relatively movable by pressure fluid, a drill actuating motor carried by and movable with one of said elements, a brake carried by the piston and engageable with the cylinder wall, means for actuating the brake comprising power transmitting means extending longitudinally in the piston, and means for controlling transmission of power thereby to the brake located at the base of said drill actuating motor and movable therewith.

13. Drill feeding mechanism comprising a feed cylinder, a feed piston therein, said cylinder and piston arranged to permit relative movement of greater extent than the length of the piston, radially expandible friction brake means and means for expanding the same carried by said piston, means for admitting fluid to effect relative movement between the cylinder and piston, and means operative either when such fluid admission is occurring or interrupted for controlling said friction brake.

In testimony whereof I affix my signature.
ELMER G. GARTIN.
